LIPSTICK CONTAINER

Robert L. McKnight, Watertown, and Willis H. Machin, Middlebury, Conn., assignors to Scoville Manufacturing Company, Waterbury, Conn., a corporation of Connecticut

Application June 21, 1940, Serial No. 341,672

9 Claims. (Cl. 206—56)

This invention relates to improvements in lipstick containers and particularly to that type of container known as a swivelly-operated lipstick.

One object of this invention is to provide a container in which various improvements have been incorporated, to cut down the cost of manufacture of the device, to design the container to facilitate the assembly and disassembly of the various parts and at the same time improve the operating mechanism so as to produce a smoother working article.

A further object is to make various improvements in the carrier cup, one having reference particularly to the operating lug that cooperates with the mechanical movements of this container for propelling the cup axially within the container, and another is so designing the carrier cup as to accommodate the various sizes of rouge stick that prevail in the market.

With the foregoing and other objects in view, which will appear as the description proceeds, the invention resides in the combination and arrangement of parts and in the details of construction hereinafter described and claimed, it being understood that changes may be made in the precise embodiment of the invention herein disclosed without departing from the spirit of the same.

In the accompanying drawing:

Fig. 1 is a central longitudinal section through a lipstick container embodying the present invention.

Fig. 2 is a front elevation of the inside shell or operating sleeve and assembled carrier cup removed from the body.

Fig. 3 is a front elevation slightly enlarged of the carrier cup disclosing particularly the new form of operating lug.

Fig. 4 is a transverse section on an enlarged scale taken along line 4—4 of Fig. 1.

Fig. 5 is a fragmentary perspective view of the open end of the container showing a means for disassembling same.

Fig. 6 is a view similar to Fig. 1 with cover removed and showing the carrier cup in partially elevated position and showing a modified construction of the operating lug.

Fig. 7 is an elevation view of a carrier lug slightly enlarged and showing a front view of this modified lug.

Fig. 8 is a view similar to Fig. 7 with the carrier cup rotated 90 degrees to show a side view of the modified lug.

Referring now to the drawing in which like

reference numerals designate like parts throughout the several views, the numeral 10 refers to an outer casing or body usually in a tubular form which, in this case, is shown made of metal but can just as well be made from any one of the various molded products, such as Bakelite, etc. Operating within the body 10 is an inside shell or operating sleeve 11 having an integral enlarged operating head 12 at its lower end, the latter providing a shoulder 12' adapted to engage against the adjacent annular end of the body 10. To rotatably hold the sleeve 11 within the body 10, the upper open end of said sleeve is flanged outwardly as at 13 and adapted to overlie the adjacent end of the body 10. A carrier cup 14 designed to move axially within the sleeve 11 serves to elevate the rouge stick 15 carried thereby as shown in dot and dash outline (see Fig. 1).

As pointed out in the objects, provision is made to improve the means for elevating and retracting the carrier cup 14. This is accomplished by providing a helical groove 16 within the inside wall of the body 10. In case the body is made of metal, the groove 16 may be formed by a spiral broaching operation, whereas if the body is made of a plastic material the groove may be formed during the molding operation. A longitudinal slot 17 is cut out of the inside shell wall and extends substantially the entire length thereof and the upper end of this slot 17 is extended through to the open end of the shell 11 by a substantially narrower slot 17'.

In order to provide a means on the carrier cup 14 to operate in the slot 17 and helical groove 16, a longitudinal strap 18 is provided in the side wall of the cup 14 as by means of spaced parallel slits or shearings 18' (see Fig. 3). Formed outwardly from the intermediate portion of this strap 18 is a projecting U-shaped operating lug 19; said lug being preferably formed on a bias to the axis of the cup 14 in conformity with the pitch of helical groove 16 and projecting through the slot 17 and into the groove 16 (see Fig. 1). Upon the rotation of the sleeve 11 relative to the body 10, the carrier cup 14 will be elevated and retracted in the usual manner of the so-called swivel type lipstick containers. The fact that the lug 19 is of U-shaped configuration and formed on a bias serves to prevent a relatively loose or sloppy fit of the cup 14 within the container, which is quite obvious in view of the manner that this particular biased U-shaped lug 19 fills up the axial width of the helical groove 16 wherever the cup 14 may be disposed within the

shell 11. This particular construction of the lug 19 (with reference particularly to the rounding portions wherein the opposite sides of the lug 19 connect integrally with the strap 18) aids materially in the operation of the device because of the ease with which the lug is adapted to slide up and down the helical groove 16. Further, if any obstruction becomes accidentally lodged in the helical groove 16, or if there is any tendency for the lug 19 to become jammed while operating in the groove 16, the fact that the lug 19 is formed at an intermediate portion of the strap 18 and sheared completely from the adjacent side walls of the cup 14 allows for a resilient radial movement of said lug 19 relative to the body of the cup 14, and thus permit the lug to clear any obstructions without jamming or ruining the container.

In order to allow for the maximum stroke of the carrier cup 14 within the container and at the same time retain its axial movement within predetermined limits, the lower edge 28 of the longitudinal slot 17 is formed on an incline comparable to the bias of the lug 19. The upper edge of the slot 17 is also similarly formed and thus provides a pair of inclined shoulders 21 on opposite sides where the narrower slot 17' merges with the long slot 17. The right shoulder 21 forms a reentrant angle with the adjacent longitudinal edge of the slot 17 and serves as a stop to be engaged by the upper end of the lug 19 when the carrier cup is in its uppermost position and thus prevent its complete ejection from the container.

In the assembly of the device, when the inside shell 11 is out of the body 10, the open end of said shell can be sprung outwardly to laterally expand the slot 17' a sufficient degree to allow the lug 19 of the carrier cup 14 to enter therethrough after which the shell 11 will spring back to the normal narrow dimension of the slot 17', thus preventing the removal of the carrier cup 14. With the carrier cup assembled and disposed at its innermost position, the upper end of the shell 11 can be collapsed, by reason of the slot 17', sufficiently to decrease the diameter of the flange 13 and allow the shell 11 to be inserted axially through the interior of the body 10. When the shell 11 is in complete assembled position, the open end flange 13 of the shell 11 will spring out automatically with the flange overlying the adjacent edge of the body 10 in locked position, yet remain sufficiently loose to permit relative rotation between the shell 11 and body 10.

If need arises to remove the inside shell 11, provision is made of a pair of relatively small apertures 22 disposed adjacent the flange 13 and on opposite sides of the slot 17'. A suitable tool 23, as illustrated in Fig. 5, having spring fingers 24 with angular prongs 25, may be employed to engage in the apertures 22 and collapse the upper end of the shell 11 so that the flange 13 will be released from the edge of the body 10 and allow the shell 11 to be removed therefrom.

One of the faults encountered in the past in the use of lipstick containers arises from the fact that the diametrical size of the rouge stick varies considerably, due to unstandardization by the stick manufacturers or to shrinkage of the stick after it is molded. With such a condition a rigid fit of the stick 15 in the carrier cup 14 could not be assured. In order to overcome this fault, it is the purpose of our invention to design the carrier cup to accommodate a rouge stick

of varying dimensions. This is accomplished by providing a pair of spaced inwardly-formed beads or knurls 26 in the cylindrical portion of the carrier cup 14. If the lipstick is of a size to fit the inside diameter of the carrier cup, it can readily be pressed down through the two beads 26 and if, on the other hand, the rouge stick happens to be of a smaller size, the beads 26 will form a sufficient bearing to support and retain the stick 15 rigidly within the carrier cup 14. As a further means of anchoring the stick 15 rigidly, a relatively long narrow lug 27 struck upwardly from the base of the carrier cup 14 is adapted to be embedded axially into the adjacent end of said stick. To provide for instances where the rouge stick 15 is of a relatively small diameter, in order to eliminate an objectionable annular clearance that would occur between the stick proper and the shell part of carrier cup 14, the upper end of the carrier cup is rolled or spun inwardly at 28 to a position where its inner edge is but slightly larger than the crest diameter of the ridges 26.

This inturned edge 28 of the carrier cup 14 also serves another useful function, as for instance where the rouge stick is larger in size and of substantially the same diameter as the inside of said cup 14. In such case when the stick 15 is assembled into the cup 14, the inturned edge 28 will serve as a knife to scrape or peel off the excess stock as the stick 15 is forced into the cup 14, after which such excess stock may readily be wiped away.

Modified form

The modified form shown in Figs. 6, 7, and 8, is the same in all respects as the first form represented by Fig. 1 except for the construction of the operating lug engaging in the helical groove 16. In this form the strap 18a, which is sheared from the body of the carrier cup 14a, has substantially its entire length disposed outwardly from the cylindrical body of the cup—a distance substantially equal to the metal thickness of the inner sleeve 11a. The operating lug 19a, the same in all respects to the lug 19, is formed outwardly from the raised strap portion 18a. By so forming the entire length of the strap 18a outwardly in the above manner, the construction provides for a greater bearing effect against the opposite longitudinal edges of the slot 17a in the sleeve 11a. With the longer bearing thus affected, the tendency of the cup to twist and bind during its movement up or down within the container is greatly decreased.

While the form of invention herein shown and described embraces two preferred embodiments of the same, it is to be understood that the construction may be varied as to mechanical details without departing from the spirit of invention and the scope of what is claimed.

What is claimed is:

1. In a lipstick container, an outer casing having a helical groove formed in its inner wall; a sleeve in said casing having an integral enlarged operation head at one end engaged against the end wall of the container and other opposite end provided with an outward flange for engagement with the opposite end wall of the container thus effecting a locking and rotatable connection between said casing and shell, said shell having a longitudinal slot in its side wall; and a carrier cup disposed within said sleeve and having a relatively long strap sheared in the side wall of said carrier cup and capable of being sprung relative

to the normal side wall of said cup, and a transverse U-shaped lug formed outwardly from an intermediate part of said strap, projecting through said slot and engageable in said helical groove whereby upon relative rotation of said sleeve to said casing said carrier cup will be advanced and retracted within said container.

2. In a lipstick container, an outer casing having a helical groove formed in its inner wall; a sleeve rotatably mounted in said casing and having a longitudinal slot provided in its side wall; a carrier cup axially movable within said sleeve, said carrier cup having a U-shaped lug sheared and formed outwardly of the side wall with its slit edges arranged parallel to the axis of the cup for slidable engagement with the longitudinal edges of said slot, and the connecting ends of said lug biased at an angle corresponding substantially to the pitch of said casing groove and designed to have a relatively snug fit in and slidably engage the opposite guiding edges of said groove whereupon relative turning of said sleeve and casing said cup will be advanced and retracted within said casing.

3. In a lipstick container, an outer casing having a helical groove formed in its inner wall; a sleeve rotatably mounted in said casing and a longitudinal slot provided in its side wall, a carrier cup axially movable within said sleeve, said carrier cup having a relatively long strap sheared in the side wall of said cup and capable of being resiliently flexed relative thereto, said strap being formed outwardly substantially the wall thickness of said sleeve and engageable in the slot thereof; and a U-shaped transverse lug formed outwardly of the strap at an intermediate position and adapted to slidably engage in said groove whereupon relative turning of said shell and casing said cup will be advanced and retraced within said casing.

4. In a lipstick container, an outer casing having a helical groove formed in its inner wall; a sleeve rotatably mounted in said casing and a longitudinal slot provided in its side wall, a carrier cup axially movable within said sleeve, said carrier cup having a relatively long strap sheared in the side wall thereof, capable of being sprung thereto and formed outwardly substantially the wall thickness of said sleeve and engageable in the slot thereof; and a lug member formed outwardly from an intermediate part of said strap at an angle corresponding substantially to the pitch of said groove and adapted to slidably engage in said groove whereupon relative turning of said shell and casing said cup will be advanced and retracted within said casing.

5. In a lipstick container, an outer casing; a cylindrical sleeve having a longitudinal slot in said casing; a carrier cup within said sleeve, said sleeve having an enlarged operating head at one end having a thrust engagement against the adjacent end of said casing, the opposite open end of said sleeve formed with a flange overlapping the adjacent end of said casing, the upper end of said slot having a continuous slot of relatively narrower width extended through the open end of said sleeve to permit the open end of said sleeve to be collapsed; and a pair of apertures provided in said sleeve on opposite side of the

narrower slot adapted to be engaged by a tool for collapsing said sleeve and permit the removal of said sleeve from said casing.

6. In a lipstick container, an outer casing having a helical groove extending in its inner wall throughout its entire length; a cylindrical sleeve rotatably mounted in said casing and having a longitudinal slot in its side wall; a carrier cup in said sleeve; a U-shaped lug formed outwardly of the wall of said cup and at an angle diagonal to the longitudinal axis of said cup, the opposite connecting ends of said lug adapted to project through said slot and slidably engage with the opposite guiding edges of said groove and operable to advance and retract said cup upon rotation of said sleeve relative to said casing, the opposite narrow edges of said slot being cut on an angle corresponding substantially to the angle of said lug for the purpose of increasing the length of travel of said cup.

7. As an article of manufacture, a carrier cup for use in a swivel type of lipstick container having a coacting longitudinal slot and a helical groove, said carrier cup having a U-shaped lug sheared and formed out of the cup material with its sheared edges arranged parallel to the cup axis, and the opposite connecting ends of said lug arranged on an angle corresponding substantially to the pitch of said helical groove and adapted to be guided by the opposite edges of said groove.

8. In a lipstick container, an outer casing having a helical groove formed in its inner wall, a sleeve rotatably mounted in said casing and having a longitudinal slot provided in its side wall; a carrier cup axially movable within said sleeve, a lug projecting outwardly from the side wall of said cup and having two opposite edges arranged parallel to the cup axis and spaced for slidable engagement with the longitudinal edges of said slot, and the other two edges of said lug biased at an angle corresponding substantially to the pitch of said casing groove and adapted for slidable engagement with the opposite guiding edges of said groove, said lug in general substantially filling the adjacent space wherever the longitudinal slot crosses the helical groove.

9. In a lipstick container, an outer casing having a helical groove formed in its inner wall, a sleeve rotatably mounted in said casing and having a longitudinal slot provided in its side wall; a carrier cup axially movable within said sleeve, a longitudinal guide projecting outwardly from the carrier cup wall of a height substantially equal to the sleeve thickness with its long edges parallel to the cup axis and slidably engaged in said longitudinal slot, a lug projecting outwardly from said guide having two opposed edges co-extensive with said guide edges and the remaining edges of said lug biased at an angle corresponding substantially to the pitch of said casing groove and adapted for slidable engagement with the opposite guiding edges of said groove, said lug in general substantially filling the adjacent space wherever the longitudinal slot crosses the helical groove.
